UNITED STATES PATENT OFFICE.

JOHN HERBERT RATCLIFFE, OF MANCHESTER, ENGLAND.

PORTABLE MIXER FOR PAINT, DISTEMPER, PASTE, OR THE LIKE.

1,120,162.

Specification of Letters Patent.

Patented Dec. 8, 1914.

Application filed March 14, 1913. Serial No. 754,306.

To all whom it may concern:

Be it known that I, JOHN HERBERT RATCLIFFE, a subject of the King of Great Britain and Ireland, residing at Gaylor Street 5 Color Works, Oldham road, Manchester, in the county of Lancaster, England, have invented new and useful Improvements in Portable Mixers for Paint, Distemper, Paste, or the like, of which the following is 10 a specification.

My invention has reference to a portable mixer for breaking down paint, mixing distemper, paste or the like and is particularly adapted for use by decorators' workmen, instead of necessitating the laborious breaking down and mixing of paint in the paint can by means of a stick or the like.

In the accompanying drawing which illustrates my invention: Figure 1 shows 20 in elevation the portable paint, &c., mixer. Fig. 2 is a plan view thereof, and Fig. 3 is a plan view of a detail part.

In a portable mixer made in accordance with my invention there is provided a rod 25 or spindle *a* carrying at its lower end mixing blades *b* *b'* of any suitable number and shape. The drawing shows three blades *b* secured to a table *b*² fast on the end of the spindle *a*, the blades being perforated as 30 shown, or these perforations may be dispensed with. A plan view of the table *b*² and mixing blades is shown in Fig. 3. A fourth blade *b'* is secured in a boss *b*³ by a set screw and is adapted to scrape around 35 the sides of the keg or can *c*, and can be adjusted to suit varying diameters of kegs. The spindle *a* is adjustable vertically in a boss *d* formed on the center of a cross bar *e*. It is intended that this cross bar shall 40 be disposed upon and be secured to the top of the paint can *c* or other receptacle containing the paint or the like which is to be broken down or mixed, and the vertical spindle *a* is made slidable within the boss *d* 45 so that the mixing blades can be fixed at varying heights according to the depth of the can. Means are provided to clamp the cross bar *e* to the can which means may be varied, but at present I find the illustrated 50 method to be suitable and which is as fol-

lows: Two end slots *f* *f* are formed in the cross bar *e* in which are freely slidable the necks *g* of jaw pieces *h*. A screw bolt *i* passes freely through a slot *i'* in the necks *g* and carries a wedge or clamping piece *j* 55 which is formed with an inclined side at *j'* the jaw *h* having also an inclined surface at *h'*. When the keg or can has been inserted in the jaw *h* as shown in section in Fig. 1 the screwed bolts *i* are rotated to 60 draw the wedges *j* upward, and so the cross bar *e* is firmly clamped upon the top of the keg or can *c*.

The jaws *h* are slideable in the slots *f*, *f* to accommodate varying diameters of paint 65 kegs, cans or the like. To drive the mixer I mount a shaft *k* horizontally in suitable bearings *m* *m* formed on the cross bar *e*, the shaft *k* having a bevel wheel *n* thereon meshing with a bevel pinion *o* secured by a 70 set screw *o'* to the vertical mixing shaft *a*. This latter bevel wheel when secured to the vertical mixing shaft *a* is adapted to drive the mixing shaft and rotate the mixing blades *b*, *b'* while permitting such shaft to 75 be adjusted endwise through it when the set screw *o'* is slackened. The horizontal driving shaft *k* is actuated by a hand wheel, handle, crank *p* or the like. The apparatus as described may be varied in matter of detail. 80

I declare that what I claim is:

In a portable mixer, in combination, a spindle, means for rotating the same, a table secured to the lower end of said spindle and 85 extending at right angles to the axis thereof, mixing blades secured to and depending from said table, a boss upon said table, a mixing blade having a right angled extension adjustably engaging said boss, and 90 means for holding said blade in its adjusted position relatively to said boss.

In testimony whereof I have signed my name to this specification in the presence of two subscribing witnesses.

JOHN HERBERT RATCLIFFE.

Witnesses:

ALFRED STUART YATES,
NORMAN KIERNAN.
